UNITED STATES PATENT OFFICE.

FRANK J. MUHLFELD, OF NEW YORK, N. Y.

NAPPED HAT WITH SHORT VELURE NAP.

1,117,886.

Specification of Letters Patent.

Patented Nov. 17, 1914.

Original application filed January 20, 1911, Serial No. 603,696. Divided and this application filed June 10, 1913. Serial No. 772,734.

To all whom it may concern:

Be it known that I, FRANK J. MUHLFELD, a citizen of the United States, residing at 805 Crotona Park North, New York, county 5 of New York, and State of New York, have invented certain new and useful Improvements in Napped Hats with Short Velure Nap, fully described and represented in the following specification and the accompanying drawings, forming a part of the same.

The present application is a division of my application No. 603,696 filed January 20, 1911 and allowed December 11, 1912 for improvements in the art of making velure hat-bodies by napping, in which I have claimed a process of making napped hats with a short dense pile resembling the nap on velure-brush-hats. The present application claims the product therein described.

20 The present invention consists of a napped hat-body and a napped hat having a close shortly piled velure nap, of fibers different from the substance of the felted body.

25 Heretofore, the so-called velure hats which have a short nap, like velvet or plush, have been produced by felting a suitable hat-body and raising a nap from the fibers of the body itself by stiffly brushing the felt. Such brushing draws out and loosens some 30 of the fibers, thus forming a short nap or pile which is afterward clipped to make fibers of uniform length, and such velure hats having the pile made by brushing, possess a close dense nap which gives a velvety 35 appearance to the finished article. Such a nap is distinguished from that upon ordinary napped hats in two respects, first, it is of the same substance as the felted body, and second, its length is a mere fraction of that 40 produced by ordinary napping fibers.

In making a silky nap by brushing, it is evident the nap that is thus raised is a part of the felted body, and it is the object of the present invention to furnish an article in 45 which the felted hat-body can be of cheaper material than the nap; thus reducing the cost.

Felted hat-bodies are formed of fur that is carotted or treated with nitrate of mercury to make the fibers mat close together 50 into a dense substance, but napping must be effected with uncarroted fibers, which are incapable of felting, as the fibers are only rooted in the felted hat-body and the projecting

portions must be entirely loose and separate 55 from one another, so as to produce a flexible coating upon the felt. The uncarroted napping fibers are first formed into a soft layer, called a "nap-bat," which is then applied to the previously felted hat-body and pressed 60 or stuck thereon with a damp cloth or by vibratory pressure; the nap-bat and previously felted hat-body are then rolled in a felting-cloth dipped in scalding water and pressed and rolled to work the base-ends of 65 the napping-fibers into the substance of the felted body so as to root them therein. When the napping is concluded, the felt is beaten and combed to dislodge any fibers which have not become rooted in the felt, 70 and to loosen the free ends of the fibers which are rooted.

To produce with napping fibers, a dense short nap resembling that upon a velure hat, has been heretofore found impracticable for 75 several reasons; partly because the napping fibers are very much longer than those which form the short velure nap, and in clipping such fibers when rooted in the hat-body to produce a short nap, the greater part of the 80 valuable material is cut off and not utilized, as such nap does not exceed one-quarter of an inch in length; and partly, because it has been found in practice that when long fibers are rooted in the felt by napping, they are 85 when clipped close to the felt, insufficient in number to form a dense velvety nap thereon, but permit the felt body to be visible through and between the fibers to a greater or less extent, thus detracting seriously from 90 the appearance of the hat.

I have discovered, as set forth in my application, No. 603,696, that it is possible to produce a dense short nap, such as is desired, by cutting the fibers to materially shorten them 95 before napping and again clipping them after they are rooted in the hat-body. By using fibers of, for instance, half the usual length, the fibers are made stiffer and are, more readily than long fibers, pushed 100 into the felt and rooted therein during the napping operation. Moreover, by using shortened fibers the great loss of fibers which is common during the scalding and beating steps of the napping operation is almost entirely avoided, because the ends of the short fibers do not become entangled like the ends 105 of long fibers in the process of napping, and

the loose fibers which are removed by the beating operation will not therefore pull with them fibers which have penetrated into the hat-body. My former application also disclosed that I may further increase the proportion of fur-fibers to the square inch of the body-felt by stretching the body-felt before it is napped, and allowing it to shrink during the napping operation. The nap-bat 10 when stuck to the hat-body is shrunk with the body, and the fibers rooted therein are concentrated upon a smaller area, which increases their density as desired.

To distinguish my new articles of manufacture clearly from prior constructions, I have illustrated my present application with the same drawings that are shown in my former application, and made claim herein to the felted hat having rooted therein clipped 20 raw fur-fibers sufficiently near together to form a close velvety nap resembling in appearance the nap on a brush-velure hat.

In the drawing, Figure 1 shows a section of a completely felted hat-body in conical form; Fig. 2 shows the same with means applied to its edge to stretch it to flat form; Fig. 3 is an edge view, and Fig. 4 a plan of the hat-body stretched into flat form. Fig. 5 is a plan of a nap-bat made of sectional 30 fibers; Fig. 6 is a cross-section of the hat-body with a nap-bat applied thereto; and Fig. 7 is a cross-section of the hat-body restored to conical form with the short nap upon its outer side. Fig. 8 shows a hat made 35 from the body of Fig. 7.

Fig. 1 shows a conical hat-body *a*, which is represented in Fig. 2 stretched nearly flat by tongs *a'*, and after the body is reduced to a flat form as at *c*, a bat *e* of raw fur, shown 40 in Fig. 5, is laid upon the hat-body and stuck in the usual manner so that the hat-body and bat assume the relation shown in Fig. 6. As the bat is of uniform thickness, the hat-body receives on all parts of the surface, substantially 45 the same number of fur-fibers to the square inch. Such hat-body and bat are then subjected to the usual sticking and scalding operations to insert the napping fibers into the felted hat-body, and the body 50 is aided and permitted to shrink back into a substantially conical form such as it possessed before stretching, thus increasing the density of the nap upon each unit of area. A napped hat-body *f* thus produced is shown 55 in Fig. 7. Such body is then blocked to any suitable shape, as shown in Fig. 8, and the napping fibers then trimmed to even length by a clipping machine. After clipping, the hat has the appearance of a brush-velure 60 hat, because the raw fur-fibers which have become rooted closely together have, by such clipping operation, been leveled so as to extend substantially to even length above the surface of the hat-body.

65 As pointed out above, the density of the

nap upon the finished hat may be increased by stretching the hat-body prior to napping, and shrinking it after napping approximately to its initial shape or dimensions.

It is not essential that my felted hat-body 70 should originally possess the conical form shown in Fig. 1, as I may employ a hat-body which has been felted into flat form, so that the apparatus shown in Fig. 2 need not be employed. I prefer, however, to 75 make my hat of a body having originally the form shown in Fig. 1, as by so doing I avoid much of the stretching of the napped hat-body, which is necessary when blocking a flat hat-body. The article thus produced 80 is distinguished from ordinary napped hat-bodies, by the following characteristics. First. The hat has a dense coating of napping fibers rooted in a previously felted hat-body and forming a closely clipped, velvety 85 nap thereon resembling in appearance the nap on a brush-velure hat. Second. Such hat has a short closely piled velure nap of fibers different from the substance of the felted body. Third. Such a napped hat (re- 90 sembling in appearance a velure hat) has a great increase in the number of fibers per unit of area above the number that is normally rooted when full length fibers are used, and is thus readily distinguished from 95 any hat napped with full length fibers.

It will be understood from the above description, that the hat claimed herein, while it resembles a brush-velure hat in outward appearance, differs therefrom in material 100 and structure, in that it has a napped hat-body, and napping fibers composed of raw fur rooted therein and covering the surface of the body so as to form a dense velvety nap thereon; the appearance of such napped 105 hat being due to the fact that the napped fibers are not only clipped after napping, but are more numerous per unit of area than would be the case had substantially full length fibers been used.

The value of the final clipping operation becomes apparent only after the fact is recognized that the raw fur-fibers are more numerous per unit of area in a hat-body napped as described above than in a hat- 115 body napped in the usual manner.

Where in the claims I speak of "short sectional" fibers, I mean fibers so rooted that they are more numerous per unit of area than would be the case if the same hat-body 120 were napped in the usual manner with fibers having substantially their full length. I find that in order to have the nap resemble that of a brush-velure hat the fibers should project from the felted body to a distance of 125 not more than approximately one-quarter of an inch, although the distance which I prefer, as usually giving better results with a hat made as above described, is less than one-quarter of an inch.

Having thus set forth the nature of the invention what is claimed herein is:

1. As a new article of manufacture, a napped hat comprising a felted hat-body having rooted therein short sectional clipped fur-fibers sufficiently near together to form a close velvety nap resembling in appearance the nap on a brush velure hat, substantially as herein described.
- 10 2. As a new article of manufacture, a napped hat comprising a felted hat body having rooted therein short sectional clipped raw fur-fibers sufficiently near together to form a close velvety nap resembling in appearance the nap on a brush-velure hat, and differing from the substance
- 15 of the felted body, substantially as herein described.
3. As a new article of manufacture, a napped hat comprising a felted hat-body 20 made of wool having rooted therein short sectional clipped raw fur-fibers sufficiently near together to form a close velvety nap resembling in appearance the nap on a brush-velure hat, substantially as herein described. 25

In testimony whereof I have hereunto set my hand in the presence of two subscribing witnesses.

FRANK J. MUHLFELD.
